UNITED STATES PATENT OFFICE.

JOSEPH WOLFINGER AND ROBERT D. BAKER, OF DUNDAS, WISCONSIN.

CAN-WASHING MACHINE.

Application filed January 15, 1926. Serial No. 81,375.

This invention relates to a can washing machine.

In canneries, various attempts have been made to wash the cans but these attempts have not been wholly satisfactory. Each has had the disadvantage of wasting a considerable amount of water and steam, and also of providing imperfect drainage for the cans. Further, the devices heretofore made have been relatively complicated and elaborate in construction.

This invention is designed to overcome the defects noted above, and objects of this invention are to provide a can washing machine in which the cans are thoroughly washed by successive applications of water and steam, in which the water and steam is very greatly conserved over present forms of can washing devices, in which there is no chance of damaging the cans, and in which a free, unobstructed and perfect drawing of the cans results.

An embodiment of the invention is shown in the accompanying drawings, in which:—

Figure 1 is a side view partly broken away showing the can washer.

Figure 2 is a horizontal view partly in section through the device.

Figure 3 is a vertical sectional view taken approximately on the line 3—3 of Figure 2.

Figure 4 is a sectional detail of the valves controlling the flow of water and steam.

Figure 5 is a sectional view on the line 5—5 of Figure 3.

Figure 6 is a sectional view on the line 6—6 of Figure 3.

Figure 7 is a vertical sectional view through one of the spraying nozzles.

Figure 8 is a section on the line 8—8 of Figure 7.

Referring to the drawings, it will be seen that the can washer comprises a compartment or hood 1, into which the cans are passed by means of the conveyor 2.

It is to be noted that the conveyor, at its upper end, is adapted to receive the cans as they are rolled thereinto, and is curved and twisted so as to stand the cans upright with their open ends presented downwardly.

The cans are advanced in a step by step manner by means of the wheel 3, such wheel being provided with a plurality of arms somewhat in the nature of a star wheel, although the arms themselves are curved and approximate circular disks. They fit into the cans, as shown in Figure 1, and as the

wheel is rotated, they advance the cans in a step by step manner.

The cans travel upon tracks 4 inside the compartment 1, such tracks being most clearly shown in Figure 2, 5 and 6. The tracks, it will be noted, are located adjacent the edges of the cans so as to leave their interior free and open. The cans are picked up after they leave the star wheel 3 by means of projecting fingers 5 carried by an endless conveyor 6 mounted in the compartment, as shown most clearly in Figure 3. These fingers, it will be noted have their upper ends directed rearwardly so that they will enter the cans without any possible chance of damaging the cans. Further, the rearwardly projecting fingers extend a considerable distance upwardly into the cans and allow them to tilt about such fingers, as shown at the left hand end of Figure 3, and to gradually assume a horizontal position. When the cans are in the horizontal position at the delivery end of the conveyor 6, they are received upon short spaced rods 7 and roll outwardly through an opening 8 in one of the vertical sides of the compartment 1 and pass along flanged tracks 9 (see Figure 2) to the filling station.

During the passage of the cans through the compartment 1, they are subjected first to a cold water spray from a nozzle 10 (see Figure 3), then through a hot water spray from the nozzle 11, and then through successive steam sprays from the nozzles 12. Further, it will be noted from an inspection of this figure and from the further description of these nozzles that the interior of the cans are subjected to a whirling spray from each nozzle, so that each part even including the crease or seam at the junction of the closed end of the can with its side walls, are thoroughly cleaned.

The cold water washes the dirt out without any caking or baking thereof. Thereafter, the hot water aids in a further cleaning and scouring of the cans, and subsequently the steam completes the sterilization and heats the cans, making them quickly dry.

It is particularly noted that during these operations, the cans stand vertically and are free to drain through the unobstructed open lower ends. There is, therefore, no possibility of slow draining on the one hand or of pocketing water on the other hand. This draining action continues even after

they have left the last nozzle. The cans are, therefore, completely drained and are highly heated by the steam when they are delivered to the cross conveyor 9, and consequently the minute amount of moisture adhering to the walls of the cans is quickly evaporated.

It is apparent that if the cans merely pass through continuously operating sprays 10 that a large waste of water and steam will occur. This, however, is not the case with the present invention as the steam and water are simultaneously turned on and off as needed. This turning on and off the steam 15 and water is automatically controlled in a very simple and novel manner.

As shown in Figures 1 and 2, a longitudinally extending shaft 13 parallels the compartment 1 and is spaced outside of such compartment. This shaft passes through fittings 14 communicating with the supply pipes for the steam and water, one valve being provided for the cold water, one for the hot water and one for the steam, it 25 being noted that the steam pipes are joined, as indicated at 15 in Figure 2. The supply hot water pipe is indicated at 16 in Figures 1 and 2, and the supply cold water pipe is indicated at 17. These fittings 14 are alike and are each provided with packing glands 18 on opposite sides which compress packing or other suitable material and thus seal the joint with the shaft 13.

35 The shaft 13 is provided with a transverse hole or port 19 drilled therethrough along a diameter and one of these holes is provided for each of the valve bodies or fittings 14 so that at each half revolution of the shaft, the fluid is turned on and, at intermediate points, is cut off.

Further, this shaft continues to the receiving end of the device and is provided with a beveled pinion 20 which meshes with a bevel gear 21 rigid upon the shaft 45 of the star wheel 3. Further, at the other end of the shaft a beveled pinion 22 is provided which meshes with the beveled pinion 23 carried by the transverse shaft 24 of the driving conveyor sprocket wheel 25, as shown in Figures 2 and 3. The arrangement of the projecting fingers 5, and the timing of the shaft 13, the star wheel 3, and the conveyor is such that the cans 50 are allowed a period of dwell over each nozzle, and the nozzles are simultaneously supplied with their appropriate fluid by means of the valves formed by the shaft 13 and the fitting 14. However, at the next motion of the conveyor, the nozzles are all 55 simultaneously closed while the cans are advanced.

The means for advancing the cans consists of a ratchet wheel 26 mounted upon the shaft 24, as shown in Figures 1 and 2.

This ratchet wheel is operated by means of a spring urged pawl 27 (see Figure 1,) which is driven by means of a pitman 28 adjustably connected to a driven crank 29, such crank being carried by the shaft of 70 the driving pulley 30. In this manner, a quick motion with a subsequent period of dwell is imparted to the conveyor and the cans are accordingly moved, as described above.

75 In reference to the conveyor 6, it is to be noted, particularly from Figures 5 and 6, that in reality the conveyor consists of a pair of spaced sprocket chains joined at intervals by transverse members 6' which 80 carry the projecting fingers 5, so as to leave a free and open space underneath the cans.

All dripping of liquid from the washer is prevented by means of the construction 85 of the hood or container 1. It is to be noted that an extended bottom 31 is provided, as shown in Figure 3, and that this bottom slants downwardly to a drain pipe 32. Further, the opening 8 is spaced above the 90 slanting portion 33 of the bottom so that by no possible chance can water escape from the compartment 1.

In order to insure a whirling action of the several sprays, a peculiar form of nozzle 95 is employed. The nozzles are all alike and, for instance, one of them 10, has been shown in section in Figures 7 and 8. The nozzle consists of a body portion 34 threaded upon the supply pipe and provided with 100 upwardly and oppositely slanting apertures 35 which extend through the web of the body portion. A recess 36 is formed in the body portion, and the fluid is rapidly spun in this recess due to the slanting passage- 105 ways or ducts 35.

The top of the recess 36 is closed by means of a disk 37 provided with a small circular aperture 38, such disk being held in place by means of the cap 39 screwed upon the 110 body portion. Obviously, when fluid, under pressure, is supplied the nozzles, such fluid passes upwardly through the passageways 35 and is rapidly spun in the recess 36. Thereafter, the spinning fluid passes through 115 the aperture 38 and consequently a spinning spray is given by each of the nozzles.

It is to be noted that provision is made for any inadvertent leak at the valves or fittings 14. For example, as shown in Figure 5, an 120 inwardly slanting V-shaped collecting member 40 is positioned below the shaft 14 and secured to the face of the container or housing member 1, and one or more small apertures 41 are formed in the vertical wall of 125 the housing or casing 1 to permit a dripping to pass inwardly into the housing or casing.

126 It will be seen that a novel form of can washer has been provided which will wash

the cans by subjecting them successively to whirling sprays of cold water, hot water and steam, and which will hold the cans vertically with their open portions downwardly so as to permit the utmost freedom of draining.

Further, it will be seen that a novel form of control for the several sprays is provided so that when the cans are not directly over the sprays the sprays are shut off to avoid waste of the washing fluids.

The cans are allowed to dwell only directly over the spray nozzle and such cans are in motion at all times when they are between such nozzles.

Although the invention has been described in considerable detail, such description is intended as illustrative rather than limiting as the invention may be variously embodied and as the scope of such invention is to be determined as claimed.

We claim:

1. A can washing machine comprising a casing through which the cans are passed, a conveyor for moving said cans through said casing with their open ends presented downwardly, a plurality of nozzles adapted to project streams of fluid into said inverted cans, means for imparting a step by step motion to said conveyor to insure a dwell of the cans over the nozzles so that a plurality of cans may be simultaneously sprayed, an elongated valve rod connected to said conveyor, a plurality of casings directly contacting with said rod, said rod having apertures therethrough cooperating

with said casings to form valves, whereby motion of said rod simultaneously controls said valves whereby fluid is projected through said nozzles only while said cans are located thereabove, and the flow of fluid is cut off when the cans are shifted from such position.

2. A can washing machine comprising a casing, a runway for leading cans to said casing, a star wheel for receiving the cans and advancing them in a step by step manner into said casing, a conveyor having a plurality of upwardly projecting arms adapted to enter the cans, a plurality of nozzles for successively projecting water and steam into said cans, means for imparting a step by step motion to said conveyor to cause said cans to dwell over said nozzles, an elongated shaft geared to the driving means for said conveyor and having a plurality of apertures therethrough, and arranged in the same plane, a plurality of valve fittings surrounding said shaft and communicating with said nozzles said valve fittings and the apertured shaft constituting a plurality of simultaneously operated valves, whereby the water and steam is turned on when the cans are positioned over the nozzles and is cut off when the cans are moved from such position.

In testimony that we claim the foregoing we have hereunto set our hands at Dundas, in the county of Calumet and State of Wisconsin.
